UNITED STATES PATENT OFFICE

2,447,915

STAPLING KIT

Thomas M. Sisk, Clovis, Calif.

Application August 8, 1946, Serial No. 689,286

3 Claims. (Cl. 224—5)

1

The present invention relates to new and useful improvements in stapling kits embodying portable means for conveniently carrying fence staples or the like on the body of a person, together with means for conveniently handling and holding the staples while driving the same into a fence post or other objects, and particularly adapted for use in cold weather for holding and driving the staples while wearing gloves.

An important object of the present invention is to provide a stapling kit of this character including a container for holding a plurality of staples in position by means of a belt attached to the waistline of a person in a manner so that staples may be conveniently removed singly for placing into driving position.

A still further object of the invention is to provide a staple holding tool constructed to grip and pick up a staple from the container by the action of inserting the tool into the container.

An additional object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompany drawings forming part hereof, wherein like numerals refer to like parts throughout, and in which:

Figure 1 is a perspective view of the container for the staples;

Figure 2 is a transverse sectional view taken on a line 2—2 of Figure 1;

Figure 3 is a perspective view showing the cover placed in position for the container to prevent loss of the staples therefrom;

Figure 4 is a side elevational view of the staple holding tool;

Figure 5 is an edge elevational view thereof;

Figure 6 is a longitudinal view taken on a line 6—6 of Figure 4, and

Figure 7 is an enlarged fragmentary perspective view of the staple gripping fingers.

Referring now to the drawings in detail wherein for the purpose of illustration I have disclosed a preferred embodiment of the invention the numeral 5 designates the staple container generally which is of channel construction including a rear wall 6 and front wall 7 curved to conform with the body of a person and a bottom 8 positioned between the lower edges of the front and rear walls and secured thereto by rivets or the

like 9. The walls 6 and 7 are closed at their ends and constructed of light weight sheet metal or other suitable material while the bottom 8 may be constructed of wood or other suitable material and is formed in its upper surface with a shallow trough 10.

The top of the container 5 is open and a front wall 7 adjacent one end of the container is cut away to reduce the height thereof as indicated at 11.

Belt attaching loops 12 are secured to the upper portion of the rear wall 6 to which a belt 13 is inserted for attaching the container to the body of a person at the waistline thereof.

The container 5 is adapted to hold a number of fence staples 14 of conventional construction, staples lying in the trough 10 of the bottom 8 in a manner as shown in Figure 2 of the drawings.

The staples are removed from the container by means of a staple lifting and holding tool designated generally at 15 and which comprises a handle 16 of rectangular shape in cross section and constructed of light weight resilient metal, wood or other suitable material.

The lower portion of the handle is split longitudinally at its narrow edges as shown at 17 to provide a pair of flat resilient legs 18 and 19. The lower portion of each leg is also split longitudinally on the flat surfaces thereof as indicated at 20 to provide a pair of resilient fingers 21 and 22 on the lower end of each leg, the lower ends of the legs being reduced in width to provide relatively narrow fingers as shown in Figure 4 of the drawings.

A slide 23 is positioned in the slit 17 between the legs 18 and 19 to function as a spreader to normally maintain the lower ends of the legs spread apart as indicated in Figure 5.

The outer surfaces of the fingers 21 and 22 of the leg 18 are formed with longitudinally rounded protrusions 24 and similar protrusions 25 are formed on the outer surface of the fingers of the leg 19, the protrusions 25 being positioned below the protrusions 24.

The outer surfaces of the fingers of the legs 18 and 19 are also formed with transversely extending grooves 26 and 27 respectively.

In the operation of the device with a quantity of staples 14 placed in the container 5 the lifting and holding tool 15 is inserted downwardly in the container at the reduced front wall 11 thereof, the protrusions 24 and 25 engaging the upper edges of the front and rear walls of the container whereby to close the fingers 21 and 22 at the lower ends of the legs 18 and 19 in a manner to enable

the fingers to enter between the sides of the staples 14 as shown in Figure 2, the spacing of the fingers enabling the same to snap the staple in the grooves 26 and 27 in gripping engagement therewith. By providing a pair of fingers 21 and 22 on each of the legs 18 and 19 the fingers will adjust themselves to compensate for the diverging angle of the sides of the staple 14 to thus firmly grip and hold the staple against twisting movement in the holder when the holder 15 is withdrawn from the container and with the staple gripped thereby. When the holder 15 is withdrawn from the container 5 the slide or spreader 23 will cause a spreading action of the legs to firmly grip the staple in a manner to hold the same in a desired position for driving into a fence post or other objects.

Provision is also made for attaching a magnetized finger 28 to the upper or rear end of the holder 15 by means of a non-conductive or insulated connector 29. The outer end of the magnetized finger 28 is bifurcated as indicated at 30 and in which is frictionally positioned a lug 31 adapted to enter between the sides of a staple while the ends of the finger 28 contact the sides thereof for lifting the staple from the container. The side edges of the finger 28 are reduced in width as indicated at 32 and the outwardly projecting lug 31 is adapted to enter between the sides of the staple to prevent twisting of the staple while being held for driving thereof.

If desired the container 5 may be provided with a flexible cover 33 secured to the bottom of the container by a band 34 and provided at its upper edge with a slide or zipper fastener 35 of conventional construction by means of which the top of the container may be closed to prevent loss of the staples while the staples are being carried.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. In combination a stapling kit comprising a container adapted to hold a quantity of staples

in a horizontal position on the bottom thereof, body attaching means for the container, and staple lifting tongs including a pair of resilient legs, protuberances on the legs to compress the legs by engagement of the protuberances with the opposed sides of the container upon insertion of the tongs therein, and means carried by the tongs for spreading the legs into gripping engagement with the sides of a staple.

2. In combination a stapling kit comprising a container adapted to hold a quantity of staples in a horizontal position on the bottom thereof, body attaching means for the container, and staple lifting tongs including a pair of resilient legs, protuberances on the legs to compress the legs by engagement of the protuberances with the opposed sides of the container upon insertion of the tongs therein, grooves in the lower outer sides of the legs for snapping between the sides of a staple to seat the staple in the grooves, and a spreader carried by the tongs to spread the legs into gripping engagement with the staple.

3. In combination a stapling kit comprising a container adapted to hold a quantity of staples in a horizontal position on the bottom thereof, body attaching means for the container, and staple lifting tongs including a pair of resilient legs, protuberances on the legs to compress the legs by engagement of the protuberances with the opposed sides of the container upon insertion of the tongs therein, grooves in the lower outer sides of the legs for snapping between the sides of a staple to seat the staple in the grooves, and a spreader carried by the tongs to spread the legs into gripping engagement with the staple, said legs being split longitudinally at their lower ends to provide a pair of resilient fingers to adjust themselves to the taper of the sides of the staple.

THOMAS M. SISK.
